UNITED STATES PATENT OFFICE.

JAMES J. LONG, OF NEW YORK, N. Y.

FREIGHT-CAR-DOOR HANGER.

1,062,599.

Specification of Letters Patent.

Patented May 27, 1913.

Application filed April 30, 1912. Serial No. 694,071.

To all whom it may concern:

Be it known that I, JAMES J. LONG, a citizen of the United States, residing at New York, in the county of New York and 5 State of New York, have invented new and useful Improvements in Freight-Car-Door Hangers, of which the following is a specification.

The invention has relation to sliding door fixtures such as hangers and is designed most especially to provide a hanger which is simple and effective in operation and which embodies a minimum number of parts which are easily accessible for renewal or to admit 10 of adjustment or for any other purpose, the hanger and adjunctive parts being housed in such a manner as to be protected from ice and rain so that the door may be moved at all times.

20 The invention consists in the novel features, details of construction and combination of parts, which hereinafter will be more particularly set forth, illustrated in the accompanying drawings, and pointed out in 25 the appended claim.

Referring to the drawings, forming a part of the specification, Figure 1 is a side view of a car door provided with fittings embodying the invention. Fig. 2 is a side view of 30 the hanger on a larger scale, parts being broken away. Fig. 3 is a cross section on the line $x-x$ of Fig. 2. Fig. 4 is a cross section on the line $y-y$ of Fig. 2. Fig. 5 is a perspective view of one of the hangers.

35 Corresponding and like parts are referred to in the following description, and indicated in all the views of the drawings, by the same reference characters.

The door fixture embodies a track 1 which 40 consists of a tube having a longitudinal slot 2 in its lower side, said tube being suspended in a manner to admit of its having a limited movement so that the lower portion of a car door may be elevated to clear the 45 clamps and swung outwardly from the car to release the door in the event of the load becoming piled against the same in such a manner as to prevent the free sliding of the door. As shown the tubular track is provided with eyes 3 which engage eye bolts or 50 like fastenings 4 secured to the car body

near the top thereof. A carriage 5 is arranged to operate within the tubular track 1 and consists of a channel bar arranged with the hollow side facing downwardly. 55 Slots 6 are formed in the side flanges of the carriage and other slots 7 are formed in the top thereof. A plurality of small wheels 8 are located at intervals in the length of the carriage and are mounted upon pins 9 constituting axles, said pins having their ends fitted in opposed longitudinal slots 6. The upper portion of each of the wheels 8 extends through a slot 7 of the carriage. This construction has been found to give the best 60 results and to reduce the friction to the smallest amount possible. Hangers 10 are bolted or otherwise secured to the under side of the top of the carriage and these hangers are fitted in mortises on the car door 11 and 65 are secured thereto by means of bolts or analogous fastenings 12. Flanges 13 are formed at the upper edge of each of the hangers, said flanges projecting from opposite sides of the hanger so as to equalize the 70 strain and load upon the carriage. The carriage may be of any length and is provided with a sufficient number of supporting wheels 8 to distribute the load upon the track and insure an easy movement of the 75 door when sliding the same into open or closed position.

From the foregoing description, taken in connection with the accompanying drawings, the advantages of the construction and 80 of the method of operation will be readily apparent to those skilled in the art to which the invention appertains, and while I have described the principle of operation of the invention, together with the device which I 85 now consider to be the best embodiment thereof, I desire to have it understood that the device shown is merely illustrative, and that such changes may be made when desired as are within the scope of the claim 90 appended hereto.

Having thus described the invention what is claimed as new, is:—

In a fixture for sliding doors, a carriage 100 consisting of a channel bar having longitudinal slots in its side flanges and top, hangers having flanges at their upper ends fitted

against the bottom of the carriage, fastenings for securing the flanges of the hanger to the carriage, wheels arranged to operate in the slots in the top of the carriage, and pins 5 receiving said wheels and having their ends mounted in the longitudinal slots formed in the side flanges of the carriage.

In testimony whereof I affix my signature in presence of two witnesses.

JAMES J. LONG.
